UNITED STATES PATENT OFFICE.

FINIS E. ROACH, OF CHICAGO, ILLINOIS.

ARTIFICIAL DENTURE.

SPECIFICATION forming part of Letters Patent No. 792,618, dated June 20, 1905.

Application filed April 9, 1903. Serial No. 151,697.

To all whom it may concern:

Be it known that I, FINIS E. ROACH, a citizen of the United States, and a resident of the city of Chicago, in the county of Cook and State of Illinois, have invented certain new and useful Improvements in Artificial Dentures; and I do hereby declare that the following is a full, clear, and exact description of the same, reference being had to the accompanying drawings, and to the letters of reference marked thereon, which form a part of this specification.

This invention relates more particularly to an improvement in the construction and means for detachably securing porcelain or other artificial facings for artificial teeth to the base adapted to receive the same.

The invention is an improvement on my prior invention as set forth in my prior United States patent for an artificial tooth, No. 651,388, issued June 12, 1900.

The object of this invention is to provide means for detachably engaging the tooth-facings of porcelain or the like with the crown, plate, bridge, or other base in such a manner as to afford a very secure, yet slightly resilient connection, thereby the better adapting the structure to withstand the stresses due to mastication and permitting ready removal for repair if injured.

The invention for convenience is shown embodied in a pivot denture or crown, though obviously it is equally adapted for plate or bridge dentures.

The invention embraces many novel features; and it consists in the matters hereinafter described, and more fully pointed out and defined in the appended claims.

In the drawings, Figure 1 is a view in front elevation of a device embodying my invention, showing the same embodied as a pivot-denture. Fig. 2 is a central vertical section of the same. Fig. 3 is an enlarged detail of the construction, partly in elevation and partly in section and separated for clearness of illustration. Fig. 4 is a perspective view of the attaching-plate. Fig. 5 is a section taken on line 5 5 of Fig. 4. Fig. 6 is a perspective view of the resilient diaphragm, showing the

same removed from the attaching-plate. Fig. 50 is a perspective view similar to Fig. 4, but showing the diaphragm in position. Fig. 8 is a perspective view of the facing pin or lug.

In said drawings a tooth-root A is shaped at the top to afford a flat seat or base for a 55 crown and drilled, as usual, to receive a central downwardly-extending pin or dowel b, secured on the under side of a cap or metal base B, as shown in Figs. 1 and 2. Said base is secured to said pin at an angle to correspond with the inclination at the top of the tooth-root and is provided with a depending peripheral flange b', which extends down over the top of the root, as shown in Figs. 1, 2, and 3, and affords a retaining-band for the 65 top of the root and also protects the top of the root from decay in a familiar manner. Said base B may, if preferred, be struck up from a single piece, forming the flange b' 70 integrally therewith, or the flange may be soldered or otherwise connected therewith, as preferred. Said base affords a flat upper surface for the attachment of the crown and may be inclined at an angle to afford the most effective seat or base possible for the crown, 75 so that downward pressure upon the denture when completed is imparted perpendicular with said base, which thus receives the stress due to mastication at the most advantageous angle.

The attaching-plate C comprises a sheet of platinum or other suitable metal struck up from a single piece, as shown, and of a width corresponding with the width of the facing D to be applied thereto. Said attaching-plate, 85 as shown, is bent at an angle to afford a bottom portion c, adapted to rest flat upon the labial side of the base B, and an upright portion c', which extends approximately in a plane of the axis of the tooth. The upper or axial 90 end c' of said attaching-plate is stamped or pressed to provide a recess in the labial side thereof. The inner wall of said recess inclines downwardly and toward the lingual side of the denture, and at a point slightly above the base a transverse slot or aperture is provided extending through said plate, as shown in Figs. 3 and 4. A narrow shoulder c² is pro-

80

85

90

95

vided in each side of said recess, as shown in Figs. 4 and 5, which are parallel and also incline downwardly and inwardly.

A resilient diaphragm E is secured in said recess in the attaching-plate and, as shown, is constructed of sheet metal shaped at one end to fit closely against the shoulders in said recess and to provide upwardly-directed parallel spring-plates e', which, as shown more fully in Figs. 2, 3, and 7, are directed obliquely to the facing D and between which is a comparatively long narrow slot, as shown in Fig. 6. The upper ends of said spring-plates e' incline toward said slot. As shown, said diaphragm is secured in said recess by means of an integral tailpiece or tang e², which extends through the aperture near the bottom of the recess in the attaching-plate, as shown in Fig. 3, and serves in part as brace between the attaching-plate and the base B, as shown in Figs. 2 and 3, and also enables the parts to be more conveniently held in the proper relation during the building of the denture. The attaching-plate is usually soldered to the base B, as shown in Fig. 2. This may be conveniently accomplished by passing the tail or tang e² of the diaphragm E through the aperture in said attaching-plate, cutting the same to the proper length to rest on the base-plate, and soldering both the attaching-plate and tang to the base, as shown in Fig. 2. The lingual side of the denture is then filled with solder or the like to afford a finish, forming a backing for the attaching-plate and exceptionally strong construction, with the diaphragm secured in said recess of the attaching-plate, as heretofore described.

Bedded in the facing D, of porcelain or the like, which is shaped to fit closely in the angle of the attaching-plate, is a pin F, of platinum or other suitable metal, headed at each end, as shown in Figs. 3 and 8, one of said heads f' being bedded in the facing and affording secure attachment for the pin with the porcelain. The other end of said pin extends through and somewhat beyond the inner face of the porcelain facing, and the head thereon inclines outwardly and downwardly, said inclination being complementary with the inclination of the inner side of the diaphragm and is adapted to engage behind the same when the facing is in position. Said pin, as shown, is comparatively broad vertically and thin laterally, being flattened centrally to engage in the slot in said diaphragm, as shown in Fig. 2, thereby acting when inserted in position and pressed downwardly to draw the facing firmly downward and inward into engagement with the attaching-plate and wedging the same securely in place because of the inclination of the attaching-plate.

The operation is as follows: The attaching-plate and diaphragm are secured in position upon the base-plate previous to the attach-

ment of the same to the root. The sides e' of said diaphragm provide downwardly and outwardly inclined surfaces which when the head f' of the pin F is inserted through said slot act to draw said facing downwardly and inwardly as the pin is forced downwardly in the slot. This draws the upper ends of the diaphragm outwardly, as shown in Fig. 2, into bearing against the adjacent surface of the facing, the pressure therein increasing as said pin is forced downwardly into the slot. The pin thus acts to bring the base and inner face or surface of the facing into positive engagement with the attaching-plate, affording a tight joint. Obviously the sides e' of said diaphragm act as resilient wedges engaging on each side of the head f', holding said porcelain facings with considerable pressure against the attaching-plate. Chloro-percha or the like is ordinarily used as a cementing material between the attaching-plate and facing, thus imposing a layer of resilient material between the same.

When excessive stress is applied upon the denture, as in mastication, the construction permits the structure to yield slightly, thus greatly relieving the stress upon the denture. It is evident, however, that there is no possibility of the facing becoming loose from mastication, inasmuch as any pressure exerted upon the facing acts to more firmly wedge the same in position. Obviously, however, should it ever become necessary to remove the facing it may readily be done by applying a slight upward pressure with a suitable tool at the joint, forcing the facing away from the attaching-plate and leaving the same exposed for inspection or repair. If preferred, the outer edges of the sides e' of the diaphragm may be soldered to the shoulders e², in which event the inner free edges on each side the slot will afford sufficient resiliency, or the inner edges may be reduced in thickness in that event to increase resiliency, as preferred.

The invention affords an exceptionally strong bridge construction, inasmuch as the bend of the attaching-plate extends below the facing and when braced with solder provides a fulcrum for pressures remote from the pin. It follows that while I have shown my invention embodied in a pivot or crown construction I do not desire to be limited to such, inasmuch as it is obvious that plate and bridge dentures of every kind can be readily constructed in accordance with my invention and that many details of construction may be varied without departing from the principles of my invention.

I claim as my invention—

1. In an artificial denture the combination with a base, of a facing of porcelain or the like, a pin secured therein, a head thereon directed obliquely and downwardly from the in-

ner side of the facing and means for securing the facing in position upon the base comprising a downwardly and outwardly inclined dia-
phragm rigidly attached to said base and hav-
ing resilient edges thereon adapted to engage
the pin.

2. A denture comprising a base, an attach-
ing-plate having a base portion adapted to be
secured on the base and a part directed axially
of the denture and having a recess in said axial
portion inclining downwardly and outwardly,
a diaphragm secured on the base and protrud-
ing through said recess, a facing of porcelain
fitted to said attaching-plate and means there-
on adapted for engagement with said resilient
diaphragm and acting when pressure is ap-
plied thereto to firmly engage the same in op-
erative position.

3. A denture comprising a base, an attach-
ing-plate having a base portion adapted to be
secured on the base and a part directed axially
of the denture and having a recess in said axial
portion inclining downwardly and out-
wardly, a plurality of shoulders in the sides of
said recess, a resilient diaphragm extending
through said recess into engagement with said
shoulders and at one end rigidly connected
with the attaching-plate, a facing of porcelain
fitted to said attaching-plate and means there-
on adapted for engagement with said resilient
diaphragm and acting when pressure is applied
thereto to firmly engage the same in operative
position.

4. The combination with a base of an attach-
ing-plate secured thereon and comprising an
upwardly-directed axial portion having an
oblique, downwardly-inclined surface thereon
provided with a vertical slot, a slotted dia-
phragm extending therethrough and rigidly
secured to the base a facing such as porcelain,
a flat, double-headed pin embedded at one end
in said facing, the head on the other end of which
inclines outwardly and downwardly and is
adapted to engage in said slot thereby secur-
ing the facing to the attaching-plate.

5. In an artificial denture the combination
with a base, of an attaching-plate rigidly en-
gaged thereon provided with an outwardly-
inclined recess, a facing seated on said plate,
resilient attaching means in said recess pro-
vided with a slot directed obliquely to said
facing and an outwardly-inclined wedge mem-

ber carried on said facing and adapted to en-
gage in said slot and draw the facing inwardly
upon said plate.

55

6. A facing for artificial dentures comprising
molded material such as porcelain, hav-
ing a laterally thin pin baked therein at one
end and at the other provided with an obliquely
downwardly and outwardly inclined head.

60

7. In an artificial denture the combination
with an artificial-tooth facing adapted to be
secured upon a base, of an attaching-plate
adapted to be fitted thereon and covering the
inner side and end thereof, a resilient connec-
tion between said attaching-plate and facing
comprising a slotted member extending
through said plate and rigidly attached to
said base, and a headed pin yieldingly engaged
therein.

70

8. In an artificial denture the combination
with an artificial-tooth facing, of an attach-
ing-plate adapted to be fitted thereon and cov-
ering the inner side and end thereof and hav-
ing a downwardly and outwardly extending
recess therein, a plurality of oppositely-dis-
posed shoulders in the walls of said recess, a
resilient diaphragm extending through said
plate and rigidly engaged on a base or the
like, upwardly-extending arms on the upper
end of said diaphragm adapted to be rigidly
engaged on said shoulders, a headed flat pin
yieldingly engaged between said arms and a
resilient cement such as chloro-percha between
said facing and attaching-plate.

85

9. In an artificial denture the combination
with a tooth-facing such as porcelain, of a lat-
erally thin pin rigidly secured thereon, a head
on the protruding end thereof, an attaching-
plate fitted to the inner face and base of the fac-
ing and having an outwardly-directed inclined
recess therein, a diaphragm extending through
said attaching-plate, upwardly-directed par-
allel spring-plates on said diaphragm provided
with inwardly-inclined ends adapted to receive
said pin and direct the head thereof behind
said spring-plates.

90

In testimony whereof I have hereunto sub-
scribed my name in the presence of two sub-
scribing witnesses.
